Patented Aug. 28, 1923.

Des. 62,946

UNITED STATES PATENT OFFICE.

JOHN HENRY HANDLEY, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

Application filed April 21, 1923. Serial No. 5,890. Term of patent 7 years.

To all whom it may concern:

Be it known that I, JOHN HENRY HANDLEY, a citizen of the United States, residing at the city of Amsterdam, county of Montgomery, and State of New York, have invented a new, original and ornamental Design for a Rug, of which the following is a specification, reference being had to the accompanying drawing, forming part thereof.

The drawing illustrates a portion of a rug, showing my new design.

I claim:

The ornamental design for a rug, substantially as shown.

Dated, April 18th, 1923.

JOHN HENRY HANDLEY.

Witnesses:

JOHN A. FARRELL,
ALICE C. BROWNE.
